APPARATUS FOR HEATING SLEEVES FOR PERMANENT WAVES

Jean Leclabart, Paris, France, assignor to Société
Anonyme Perma, Paris, France, a company of France

Filed Mar. 20, 1968, Ser. No. 11,054

Claims priority, application France Oct. 9, 1967

Term of patent 14 years

Int. Cl. D23—03

U.S. Cl. D23—77

FIG. 1 is a front view of the apparatus for heating sleeves showing my new design;

FIG. 2 is a top view of the apparatus of FIG. 1;

FIG. 3 is a rear view of the apparatus of FIG. 1;

FIG. 4 is a side view of the apparatus of FIG. 1; and FIG. 5 is a bottom view of the apparatus of FIG. 1.

I claim:

The ornamental design for an apparatus for heating sleeves for permanent waves, substantially as shown.
